Primary Examiner — Susan Bennett Hattan*Assistant Examiner* — Suzanne E Tisdell(57) **CLAIM**

The ornamental design for a solar module, as shown and described.

DESCRIPTION

FIG. 1 is a top perspective view of a solar module, according to an embodiment of the design;

FIG. 2 is a top view of the solar module, according to the embodiment of FIG. 1 of the design;

FIG. 3 is a bottom view of a solar module of all embodiments of the present design;

FIG. 4 is a left side view of a solar module according to all embodiments of the present design;

FIG. 5 is a right side view of a solar module according to all embodiments of the present design;

FIG. 6 is a front side view of a solar module according to all embodiments of the present design; and,

FIG. 7 is a back side view of a solar module according to all embodiments of the present design.
